(57) **CLAIM**

The ornamental design for a bottle pressurizer, as shown and described.

DESCRIPTION

FIG. 1 is a top, front, right side perspective view of a bottle pressurizer showing our new design;

FIG. 2 is a right side elevation view thereof;

FIG. 3 is a front elevation view thereof;

FIG. 4 is a left side view thereof;

FIG. 5 is a rear elevation view thereof;

FIG. 6 is a top plan view thereof; and,

FIG. 7 is a bottom plan view thereof.

The dash-dash broken lines represent portions of the bottle pressurizer that form no part of the claimed design. The short dash-long dash broken lines define boundaries of the claimed design and form no part of the claimed design.
